DONALD F. WHITING, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

1,378,392.

Specification of Letters Patent. Patented May 17, 1921.

Application filed December 26, 1919. Serial No. 347,409.

To all whom it may concern:

Be it known that I, DONALD F. WHITING, a citizen of the United States, residing at New York, in the county of Bronx, State of New York, have invented certain new and useful Improvements in Signaling Systems, of which the following is a full, clear, concise, and exact description.

This invention relates to signaling systems employing a transmission line over which currents of different frequencies may be transmitted at different times, as, for example, talking and signaling currents. The object of the invention is to make such a system efficient for transmitting currents of either frequency.

As usually designed transmission lines containing transformers or other localized inductance transmit most efficiently currents of the particular range of frequencies which it is expected to employ and are relatively inefficient for transmitting currents of other frequencies. Such lines may, however, be rendered efficient for transmitting currents of the other frequencies by connecting into the lines, in suitable relation, other elements of inductance or capacity or by changing the value or relation of existing elements. The present invention contemplates providing in a system of this character means responsive to currents of other frequencies transmitted over a line for altering the character thereof, to make it more efficient for transmitting currents of such other frequencies. The invention in the present application is illustrated as applied to a telephone transmission line containing an amplifier for amplifying both talking and signaling currents and arranged normally to be efficient for transmitting talking currents, to provide for altering the condition of the line when signaling current is transmitted.

For a more complete understanding of this invention, reference should be had to the following description considered in connection with the accompanying drawing, which shows diagrammatically the equipment at a repeater station of a two-wire-telephone repeater circuit containing an embodiment of this invention.

In the drawing there are shown two line sections 20 and 40 in each of which are connected the secondary windings of output repeating coils 21 and 41, respectively.

Connected with the line section are artificial lines 22 and 42 for balancing the respective line sections with respect to outgoing currents. An amplifier 23 of the usual construction for amplifying both talking and signaling currents has its input circuit connected through an input repeating coil 24 and through a balanced potentiometer 25 to the line section 20, the connection being at the mid-point of the secondary 60 windings of the output coil 21. The potentiometer is for the purpose of controlling the amount of talking current admitted through the coil 24 to the input circuit of the amplifier 23. The output circuit of the 65 amplifier 23 is connected with the primary winding of the output repeating coil 41 whose secondary windings are connected in the line section 40. In a similar manner the input circuit of an amplifier 43 is connected 70 through an input repeating coil 44 and a balanced potentiometer 45 with the line section 40, the output circuit thereof being connected with the primary winding of the output repeating coil 21 whose secondary 75 windings are connected in line section 20. A condenser 26 connected in the middle of the potentiometer bridge 25 is of low impedance to talking currents and is of such capacity that it forms with the winding of 80 a ringing response signal controlling relay 27, connected in parallel therewith, a loop circuit tuned to the frequency of the ringing or signaling currents. The ringing response relay 27 controls the normally energized switching relay 28 which, when de-energized, connects a condenser 29 in parallel with the primary windings of the input repeating coil 24 to form a loop circuit 85 tuned to the frequency of the signaling current, and short-circuits the primary winding of the input repeating coil 44 thereby preventing signaling current traversing the line section 40 from being repeated back 90 into the line section 20 when signaling current is incoming over the line section 20. Condenser 46 and ringing response relay 47 are similarly connected with potentiometer 45, and relay 47 similarly controls a switching relay 48. Relay 48, in releasing, 95 connects a condenser 49 in parallel with the primary winding of the input repeating coil 44 to form a loop circuit tuned to the frequency of the signaling current, and short-circuits the primary winding of the input 100

repeating coil 24. Condensers 30 and 50 prevent the flow of direct current through the primary winding of the respective output coils 21 and 41.

5 Talking current incoming over the line section 20 passes through the potentiometer 25 and the windings of the input repeating coil 24 into the input circuit of the amplifier 23. This amplifier amplifies such talking currents and transmits the amplified currents into the line section 40 through the windings of the output repeating coil 41. The condenser 26 being of low impedance to currents of talking frequencies prevents 10 relay 27 from being affected by these currents. Furthermore, the ringing response relay is of high impedance to and is non-responsive to currents of the talking frequencies. Talking currents incoming over 15 the line section 40 will be amplified by the amplifier 43 and transmitted into the line section 20 in a similar manner without affecting the ringing response relay 47.

20 Signaling current incoming over the line section 20 passes into the input circuit of the amplifier 23 in the same manner as talking currents admitted thereto and the amplified signaling currents are transmitted through the repeating coil 41 to the line section 40. The condenser 26 is of high impedance to currents of the signaling frequency, and the loop circuit formed by the condenser 26 and the winding of the ringing response relay 27 becomes effective 25 when signaling current is impressed upon the terminals of this circuit so that currents are set up therein. These large currents which apparently oscillate when a comparatively small amount of current 30 of the proper frequency is applied to the terminals of the loop are the result of resonance occurring in the loop. The action taking place may be explained in the following manner. The current flowing 35 through relay 27 lags behind the applied electromotive force by a considerable phase angle. This current may be considered as consisting of two components, one in phase and one in quadrature to the applied electromotive force. The current flowing through 40 condenser 26 consists mainly of one component which is in quadrature phase relation to the applied electromotive force and leading the latter by approximately 90 degrees. At resonance the two quadrature 45 components of currents are mutually opposite in phase and equal in magnitude and therefore nullify one another when flowing in the same circuit. Therefore, the current flowing into the terminals of the loop circuit is the in-phase component only of the current passing through the winding of relay 27. Thus with a constant value of electromotive force applied across the winding 50 of relay 27, the current entering the circuit

is decreased in value and brought into phase with this applied electromotive force by the application of the condenser 26 of the proper value. This decrease of current with a given applied electromotive 55 force is equivalent to an increase in the effective resistance of the relay, and this increase is effected with no loss of energy. Because of this increase in the effective resistance of the loop circuit including the relay (at the resonant frequency), the relay receives a greater proportion of the total energy flowing about the circuit of which the loop circuit is a part, resulting in a considerable amount of discrimination in 60 favor of that frequency. This loop circuit therefore presents a comparatively high impedance to currents of signaling frequency impressed upon its terminals. This impedance is much more than that of either 65 the condenser or the relay forming the loop. Therefore, when signaling current is transmitted, the tuned circuit becomes effective to practically open-circuit the potentiometer bridge thereby permitting more current to pass into the input circuit of the amplifier. The local oscillatory currents set up in the loop circuit causes the energization and operation of ringing response relay 27 which opens its contact causing the 70 release of relay 28. The closure of the left-hand contact of relay 28 connects the condenser 29 in parallel with the primary winding of the input repeating coil 24 thereby forming a loop circuit tuned to the 75 frequency of the signaling current. The effect of the condenser 29 upon the primary winding of repeating coil 24 is similar in every detail to the effect of the condenser 26 upon the winding of relay 27 as previously explained. The effective resistance of the loop circuit containing condenser 26 and the input coil 24 is thus raised by means of resonance until it is approximately equal to the effective resistance of 80 the circuit joined thereto, this condition resulting in the maximum transmission of currents of the signaling frequency into the amplifier 23. The closure of the right-hand contact of relay 28 short-circuits the 85 primary winding of the input repeating coil 44 thereby preventing any signaling currents which may pass through the potentiometer 45 due to any unbalance between the line and section 40 and its artificial line 42 from passing into the amplifier 43. Upon the cessation of signaling current over the line section 20, relay 27 releases and relay 28 operates, restoring the 90 circuit to normal condition. When ringing or signaling current is incoming to the repeater station over the line section 40, the relays 47 and 48 function in a manner similar to relays 27 and 28 and the incoming 95 signaling current is amplified and trans-

mitted into the line section 20 in the same manner as described for current incoming in the opposite direction.

What is claimed is:

5. 1. In a signaling system, in combination, two line sections, an amplifier for amplifying talking and signaling currents whose output circuit is connected with one line section, an input transformer connecting the 10 input circuit of the amplifier with the other line section, means associated with the other line section for controlling the amplification of the amplifier to currents of talking frequencies, a loop circuit tuned to current of 15 the signaling frequencies associated therewith and rendered effective when signaling current is impressed upon the terminals thereof to alter the effect of the amplifier controlling means upon the signaling currents, and a switching means included in 20 said circuit.
2. In a signaling system, in combination, line sections, an amplifier for amplifying both talking and signaling currents having 25 its output circuit connected with one line section, a repeating coil connecting the input circuit of the amplifier with the other line section, means in circuit with said other line section controlling the amplification of the 30 amplifier to currents of the talking frequencies, a loop circuit tuned to currents of the signaling frequency and rendered effective when signaling current is impressed upon the terminals thereof to alter the effect 35 of the amplifier controlling means at signaling frequency, a relay in the loop circuit, and a condenser connected in circuit with the primary winding of the repeating coil by the operation of the relay to form a second loop circuit tuned to currents of the 40 signaling frequency.
3. In a signaling system, in combination, line sections over which both talking and
- signaling currents are transmitted, a repeating coil joining the line sections, current regulating means in circuit with one line section for controlling talking current 45 admitted to the repeating coil, a condenser in circuit with the current regulating means, a relay in parallel with the condenser and 50 forming therewith a loop circuit tuned and rendered effective by signaling currents impressed upon the terminals thereby to alter the effect of the current regulating means at signaling frequency, and a condenser connected in circuit with a winding of the repeating coil by the operation of the relay to 55 form a second loop circuit tuned to signaling currents.
4. In a signaling system, in combination, 60 two line sections, two repeaters for amplifying talking and signaling currents, each repeater having its output circuit associated with one line section, a repeating coil for each line section, each connecting with one line section the input circuit of the repeater whose output circuit is associated with the other line section, current regulating means 65 associated with each line section for controlling talking current admitted to the associated repeating coil, a loop circuit tuned to currents of the signaling frequency associated with the current regulating means and rendered effective when signaling current is impressed upon the terminals thereof to alter the effect of the current regulating means in response to signaling currents, and means included therein and responsive to such impression of the signaling current to establish a short circuit of the line winding of the repeating coil connected with the other section. 70
